US0D1084805S

(12) United States Design Patent (10) Patent No.: US D1,084,805 S
(45) Date of Patent: * Jul. 22, 2025

(54) FASTENING DEVICE

(71) Applicant: Gunnersbury Global Trade Limited,
Dublin (IE)

(72) Inventor: Adrian Ichim, Dublin (IE)

(73) Assignee: Gunnersbury Global Trade, Ltd.,
Dublin (IE)

() Term: 15 Years

(21) Appl. No.: 29/922,812

(22) Filed: Dec. 26, 2023

(30) Foreign Application Priority Data

(57) CLAIM

The ornamental design for a fastening device, as shown and described.

DESCRIPTION

FIG. 1 is a perspective view of a fastening device showing my new design;

FIG. 2 is a front view thereof;

FIG. 3 is a left view thereof;

FIG. 4 is a back view thereof;

FIG. 5 is a right view thereof;

FIG. 6 is a top view thereof; and,

FIG. 7 is a bottom view thereof.

The broken lines are for environmental purposes only and form no part of the claimed design.

1 Claim, 7 Drawing Sheets
